UNITED STATES PATENT OFFICE.

JOHN TEN EYCK HILLHOUSE, OF NEW YORK, N. Y.

IGNITION SYSTEM FOR INTERNAL-COMBUSTION ENGINES.

1,229,266.

Specification of Letters Patent. Patented June 12, 1917.

Application filed June 3, 1911. Serial No. 631,117.

To all whom it may concern:

Be it known that I, JOHN TEN EYCK HILLHOUSE, a citizen of the United States, and a resident of the borough of Manhattan, in the city of New York, in the county and State of New York, United States of America, have invented certain new and useful Improvements in Ignition Systems for Internal-Combustion Engines, of which 10 the following is a specification.

My invention relates to improvements in ignition systems for internal combustion engines, and its object is to provide a simple arrangement to be used in conjunction with 15 high tension or jump spark systems of ignition which shall have advantages over such devices as have hitherto been in use.

I will describe my invention in the following specification and point out the novel 20 features thereof in the appended claims.

Referring to the drawings Figure 1 is a sectional side elevation of a preferred form 25 of distributor which I have invented. Fig. 2 is another sectional elevation of a portion 30 of the device which is shown in Fig. 1, this section being taken at right-angles to the section shown in the latter figure. In Fig. 3 a sectional plan view of this device is shown, the section in this figure being taken on the 35 line 5—5 of Fig. 1. Fig. 4 is an elevation of the rotary contact device shown in Fig. 1, taken in the direction indicated by the arrows 6, 6.

Fig. 5 is a plan view of a modified form 35 of a part of such a structure as is shown in Fig. 1. Fig. 6 is a sectional side elevation of another modification of my invention and Fig. 7 is a plan view of a part of the device shown in Fig. 6.

40 Like characters of reference designate corresponding parts in all of the figures.

The construction of distributor which is shown in Figs. 1, 2 and 3, is a preferred form. In this case a stationary circular housing 50 is shown surrounding the shaft 14. This housing carries a bowl-shaped body of insulation 51, in which are embedded stationary contacts 52, 53, 54 and 55 which are connected in the usual way, with 45 the wires leading to the spark coil. These contacts are also connected, respectively, with metallic strips 56, 57, 58 and 59 which are embedded in the insulation 51 and are

separated from one another. The upper surfaces of these strips are in a common horizontal plane slightly above the upper surface of the insulation 51.

60 is a movable circular housing above the stationary housing 50. The shaft 14 projects through this housing and its lower 60 edge fits over a shoulder which is turned in the upper edge of housing 50 to receive it. A body of insulation 61 is carried to this upper housing, and in it are embedded four contacts corresponding with the contacts in 65 the lower stationary housing. Three of these contacts are shown and are designated by 62, 63 and 64. The other one which is not shown in the drawings is above the contact 55. These contacts are connected with 70 metallic strips such as 66, 67 and 68, corresponding in number and in position with the strips 56, 57, 58 and 59.

On top of the movable housing 60 is a spring 70 which is compressed by a nut 71 75 on the upper end of the shaft 14, which is threaded to take it. This forces the four strips in the upper housing against the four strips in the lower housing so that they are in electrical contact with one another. 80 These contacts are arranged to slide over each other rotatably. The contacts 52 and 62 are connected together as are also contacts 53 and 63, 54 and 64, 55 and the contact above it (not shown). 72 is an arm 85 or lever projecting from the housing 60 by means of which it may be rotated relative to the fixed housing 50.

Pivoted in the shaft 14 at 73 is an arm 74 which rotatably carries a round shank 90 75, on the lower end of which is a head 76. This head carries a pivot 77 for a pair of contact rollers 78, 78. This pivot is transverse to the axis of the shank 75 but is offset therefrom as may be seen in Fig. 4. If 95 desired, a spring 79 may be interposed between the end of the arm 74 and the head 76.

The operation of this device is as follows; When the engine to which this device is attached is at rest, the arm 74 and the parts 100 which it carries will drop down of their own weight into the positions in which they are shown in Fig. 1. When the engine rotates slowly, as it will by being started by hand, the contact rollers will be moved 105 around with the shaft 14 and will run in

a plane substantially at right-angles to the axis of the shaft. In doing this they will pass successively over the lower set of contacts. But these are fixed in such relation to the shaft 14 and in relation to the travel of the pistons of the engine, that no back-firing can occur in the engine cylinders when the contact rollers complete circuits by passing over these lower contacts.

- 10 As soon as the engine runs it will rotate the shaft 14 at a considerable rate of speed, and the contact rollers with their supporting mechanism will be raised by centrifugal force. The rollers are so spaced that 15 the outside or upper one will run onto the upper contacts before the other one leaves the lower contacts so that the sparking operation will not be interrupted. But as soon as the engine attains a normal speed, the 20 contact rollers will touch only the upper set of contacts. These are mounted in the movable housing 60 so that they may be moved together by means of the lever 72 to advance or retard the spark in the usual manner.
- 25 The same centrifugally actuated rotary contact device may be used inside of the stationary housing 80 which is shown in Fig. 5. This contains a cup-like body of insulation 81, into which are set four fixed 30 contacts 82, 83, 84 and 85. The inner and lower ends of these contacts are so spaced that as the contact rollers 78 pass over them, they will cause sparks to be produced in the engine cylinders at such intervals as to fire 35 the charges therein after the pistons have reached or passed the upper limits of their paths of travel. But these contacts are curved out of axial alignment in a direction opposite to the direction of travel of the 40 rollers, which direction is indicated in this figure by the arrow 86, so that as these rollers are raised by centrifugal force they come into contact with these stationary contacts at earlier parts of their paths of travel.
- 45 And the higher they are raised the earlier will these electrical connections be made. Thus, the spark will be advanced automatically as the engine accelerates. An engine equipped with this device need have no manual adjustment for the spark. Obviously, a 50 manual adjustment may be added if thought desirable. But without a manual spark adjustment the engine's speed may be controlled entirely by the usual throttle control.
- 55 It is to be noted that the contacts such as 54 and 64 in Fig. 1 are electrically connected together and that the rollers 78 are so spaced that they will always strike against one or 60 the other of them during each revolution of the shaft so that they, in effect, form a continuous contact, one part of which may be advanced ahead of the other part. In Fig. 5, on the other hand, the contact 65 84 may be considered to comprise a lower part

and an upper part electrically connected together because integral, with the upper part advanced ahead of the lower part.

The structure shown in Figs. 6 and 7 is a combination of lower and upper contacts 70 electrically connected together. These are set in a housing 90, the inner cup-shaped portion of which is a body of insulating material 91. The lower contacts are designated by 92, 93, 94, and 95, and these are 75 so shaped and related to the other part of the apparatus that when rollers 78^A pass over them, they will cause the ignition sparks to occur in the engine cylinders at or after the times the pistons therein have 80 reached the uppermost points in their paths of travel.

Then as the engine accelerates and the rate of rotation of the shaft 14 consequently becomes greater, the arm 74^A which supports the rollers will swing about its path until the path of the rollers will bring them onto the upper contacts 92^A, 93^A, 94^A, and 95^A, which are set oblique to radial planes, like those shown in Fig. 5. These are electrically connected with the contacts immediately below them and the rollers 98^A will strike them before they run off from the lower contacts. If it is desired to have the positions of the upper contacts manually 90 adjustable relative to those of the lower contacts, the housing 90 may be divided at the lines A A by some such arrangement as that shown in Fig. 1.

Fig. 6 also shows the spring adjustment 100 for regulating the effect of centrifugal force on the arm 74^A. This device may, of course, be applied, if desired, to the structure shown in Fig. 1.

96 is a collar affixed to the shaft 14, and 105 97 is a short lever projecting from the arm 74^A. Between these is a spring 98, the compression of which may be varied by means of a nut 99.

When I speak of "sets" of contacts over 110 which the rotary contact arm passes, I mean, of course, a number of contacts corresponding with the number of cylinders of the engine to which the device is to be applied which may be one, two, three, four or 115 more.

What I claim is.—

1. In an ignition system, a distributor having two sets of contacts, one of said sets being fixed and the other adjustable relative to said fixed set, and means for rendering one or the other of said sets operative.

2. In an ignition system, a distributor having two sets of contacts, one of said sets being fixed and the other adjustable relative to said fixed set, said sets of contacts being connected together in parallel, and automatic means for rendering one or the other of said sets operative.

3. In an ignition system, a distributor 130

having a rotary contact arm, a pivoted connection therefor whereby said arm has a movement transverse to its rotary movement, and a contact over which said arm travels, said contact being so arranged that the arm will engage it in different angular positions as it moves about its pivot to automatically adjust the timing of the ignition.

4. In an ignition system, a distributor having a vertical rotary shaft, a contact arm pivotally connected therewith and arranged to have a vertical movement under the action of centrifugal force, a fixed contact and an adjustable contact above the

fixed contact, said contact arm being arranged to pass over the fixed contact when the rotary shaft is moved slowly, and over the adjustable contact when said shaft moves at a higher rate of rotation.

5. In an ignition system, a distributor having a vertical rotary shaft, a contact arm pivotally connected therewith, a fixed set of contacts, and an adjustable set of contacts above the fixed contacts and connected

25 in parallel therewith.

6. In an ignition system, a distributor having a vertical rotary shaft, a contact arm pivotally connected therewith, a two-part cup-shaped housing having its inner surfaces corresponding with the radius of the contact arm, the lower part of said housing being stationary, and the upper part rotarily adjustable relative to said lower part, a contact set in the lower part of the

30 housing, and a similar contact set in the upper part of the housing.

7. In an ignition system, a distributor having a vertical rotary shaft, a contact arm pivotally connected therewith, a two-part cup-shaped housing having its inner surfaces corresponding with the radius of the contact arm, the lower part of said housing being stationary and the upper part rotarily adjustable relative to said lower part,

45 a contact set in the lower part of the housing, a similar contact set in the upper part of the housing, and a sliding connection between said contacts.

8. In an ignition system, a distributor having a vertical rotary shaft, a contact arm pivotally connected therewith, a two-part cup-shaped housing having its inner surfaces corresponding with the radius of the contact arm, the lower part of said housing being stationary and the upper part rotarily adjustable relative to said lower part, a series of contacts set in the lower part of the housing, a similar series of contacts set in the upper part of the housing, and sliding contacts connecting said two series of contacts together in parallel.

9. In an ignition system, a distributor having a vertical rotary shaft, a contact arm pivotally connected therewith, a two-part cup-shaped housing having its inner sur-

faces corresponding with the radius of the contact arm, the lower part of said housing being stationary and the upper part rotarily adjustable relative to said lower part, a series of contacts set in the lower part of the

70

housing, a similar series of contacts set in the upper part of the housing, sliding contacts connecting said two series of contacts together in parallel, and a spring arranged to hold the two parts of the housing

75

together at said sliding contacts.

10. In an ignition system, a distributor having a vertical rotary shaft, a contact arm pivotally connected therewith and arranged to have a vertical movement under the action of centrifugal force, adjustable means for opposing said vertical movement, a spindle axially rotatable in said arm, a pair of rollers, a pivot therefor transverse to said spindle and offset from the axis

80

thereof near the end of the spindle, a cup-shaped housing, a contact therein, said contact being so arranged that the rollers will engage it in different angular positions as the arm moves about its pivot to automatically adjust the timing of the ignition.

90

11. In an ignition system, a distributor having a vertical rotary shaft, a contact arm pivotally connected therewith, a spindle axially rotatable in said arm, a pair of rollers a 95 pivot therefor transverse to said spindle and offset from the axis thereof near the end of the spindle; a two-part cup-shaped housing having its inner surfaces corresponding with the radius of the contact arm, the lower part of said housing being stationary and the upper part rotarily adjustable relative to said lower part, a contact set in the lower part of the housing, a similar contact set in the upper part of the housing, and a 100 sliding connection between said contacts, said rollers being arranged to pass over the contacts in said housing.

105

12. In an ignition system, a distributor having a vertical rotary shaft, a contact arm pivotally connected therewith, a spindle axially rotatable in said arm, a pair of rollers, a pivot therefor transverse to said spindle and offset from the axis thereof near the end of the spindle; a two-part 110 cup-shaped housing having its inner surfaces corresponding with the radius of the contact arm, the lower part of said housing being stationary and the upper part rotarily adjustable relative to said lower part, a series of contacts set in the lower part of the housing, a similar series of contacts set in the upper part of the housing, sliding contacts connecting said two series of contacts together in parallel, and a spring 115 arranged to hold the two parts of the housing together at said sliding contacts; said rollers being arranged to pass over the series of contacts in the lower part of the housing when the shaft is rotating slowly,

120

125

130

and over the series of contacts in the upper part of the housing when said shaft moves at a higher rate of rotation, and a spring arranged to press said rollers against the contacts.

13. In an ignition system, a distributer having a rotary contact arm, a pivoted connection therefor whereby said arm has a movement transverse to its rotary movement under the action of centrifugal force, adjustable means for modifying the effect of the centrifugal force on said arm, and

contacts set one above the other over which the arm travels, said contacts being so arranged that the arm will strike them in different angular positions as it moves about its pivot. 15

In testimony whereof I have signed my name to this specification in the presence of two subscribing witnesses.

JOHN TEN EYCK HILLHOUSE.
